UNITED STATES PATENT OFFICE.

JAMES A. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

RESILIENT SHANK STIFFENER.

Application filed December 3, 1924. Serial No. 753,643.

This invention relates to resilient arch supporting shank stiffeners commonly known as "spring shanks" and to boots and shoes provided with shank stiffeners of this 5 type.

Resilient shank stiffeners are intended to preserve the normal longitudinal curvature of the shank portions of shoe soles without destroying the flexibility of the soles. Accordingly, such stiffeners, as usually constructed, are curved lengthwise to conform to the longitudinal arch of the shank portions of the boots or shoes in which the stiffeners are incorporated and the stiffeners are made sufficiently flexible to yield readily so as not to prevent the desired flexing of the soles at the shank. Thus, by preserving the arched formation of the shank of the shoe, a resilient shank stiffener is capable of affording a substantial amount of support for the arch of the foot although, being capable of yielding readily, such a stiffener will not interfere with the natural flexure of the foot in walking.

Heretofore, spring shanks, so-called, have been constructed and arranged so as to yield to such a degree that not only will they permit the entire flattening of the arch of the sole and the complete collapse of the longitudinal arch of the foot but, because of the excessive flexing of the stiffener after extended periods of use, the stiffeners are liable to break at or near the middle of the arch, thus rendering them useless and making it necessary to have the shoe repaired.

In view of the foregoing, one object of the present invention is to provide an improved resilient arch supporting shank stiffener which will be flexible enough to respond readily to normal changes in foot arch curvature but which nevertheless, when incorporated in a shoe, will be incapable of excessive bending or flexing, and thus will insure against undue flattening of the arch of the sole or the arch of the foot, and which will not be liable to break but may be relied upon to perform their intended functions throughout the life of the shoe.

To the accomplishment of this object, and in accordance with one feature of the invention, the improved shank stiffener consists of a longitudinally arched strip having, substantially midway between its ends, a portion offset or bent transversely of the strip 65 an amount less than the height of the arch,

for co-operation with the sole of a shoe in which the stiffener is incorporated to limit the extent to which the stiffener strip may be straightened. The offset portion is formed by bending the strip transversely, and preferably, and as herein shown, is in the form of a U-shaped loop which extends entirely across the strip. Being offset from the strip an amount less than the height of the arch the loop will act as a stop which, by engagement with the outer sole, will prevent the strip from flattening beyond a predetermined maximum amount and thus will accomplish the desirable results above referred to. Not only will the loop prevent excessive flattening of the longitudinal arch of the strip in such a way as to tend to weaken the strip or to permit entire collapse of the arch of the shoe, or the arch of the foot, but even after the bottom of the loop has engaged the outer sole of the shoe, the stiffener does not become entirely rigid but is still capable of yielding at either side of the loop. The yielding of the strip under these circumstances, however, is distributed over portions of the strip removed from the middle portion thereof and has no tendency to weaken the strip in such a manner as to make it liable to break.

In applying the improved shank stiffener to a shoe it may be inserted between the soles without being secured to either, or it may be secured by tacks, rivets or the like at either or at both ends. If secured only at one end it will probably be desirable to secure it at the heel end. The unsecured end of the stiffener will then be free to slide between the soles to facilitate flexing of the stiffener. If, as illustrated in Fig. 2, both ends of the stiffener are firmly secured by rivets to the outer sole of the shoe, the flexing of the strip under pressure will be permitted by the looped portion thereof, the sides of which will be capable of approaching each other to permit the strip to flatten.

The features of the invention will be understood from the following description, reference being had to the accompanying drawings, in which

Fig. 1 is a perspective view of the improved shank stiffener;

Fig. 2 is a view, partially in side elevation and partially in section, of a welt shoe provided with a shank stiffener such as shown in Fig. 1; and

Fig. 3 is a perspective view of an alternative form of shank stiffener.

Referring first to Fig. 2 of the drawings, a welt shoe is therein illustrated comprising an upper 4, an innersole 6, and an outer sole 8. As shown at 10 the innersole is spaced away from the outer sole at the shank by means of a shank stiffener 12 which is curved or arched longitudinally to conform substantially to the normal, longitudinal arch of a foot which the shoe is designed to fit and which imparts a corresponding longitudinal curvature or arched formation to the shank portion of the innersole, thus providing support for the arch of the foot. To enable the stiffener and the shank portion of the innersole to yield readily under the weight of the wearer of the shoe the shank stiffener 12, as illustrated, consists of a resilient metallic strip and in order to prevent excessive flexing of the strip the strip is formed, substantially midway between its ends, with a transverse bend or loop 14 designed to function as a stop positively to limit the straightening or collapsing movement of the stiffener so as to prevent the arch of the foot from being flattened beyond a predetermined extent. As will be apparent from an examination of Fig. 2, the loop is bent at right angles to the length of the stiffener and is open at the convex side of the strip. The base or closed end of the loop 14 is spaced from the outer sole a sufficient distance to permit the arch of the foot to straighten only to a limited extent to avoid injury to the foot. After such straightening of the arch has been effected, the base of the loop 14 engages the outer sole and positively prevents further flattening or yielding of the central portion of the shank stiffener and corresponding further collapse of the arch of the foot. The loop 14 may be substantially U-shaped as shown in Figs. 1 and 2, or it may be of any suitable form such, for example, as that shown at 16 in Fig. 3. The opposite sides of the loop are spaced apart so that, in case both ends of the strip are firmly secured to the sole of the shoe, as shown in Fig. 1, the stiffener will still be resilient inasmuch as the opposite sides of the loop may approach each other under pressure tending to flatten out the stiffener. After the loop 14 has been depressed into engagement with the outer sole, however, the portions of the shank stiffener at either side of the central loop are capable of yielding more or less independently of each other, under excessive pressure, for the purpose of cushioning the sole of the foot from the effects of any sudden or unusual shock such as might result from running or jumping. The material of the stiffener may, however, be made of such stiffness that, under ordinary conditions, little if any resiliency will be apparent after the loop 14 has seated upon the outer sole.

Thus, after the stiffener has yielded sufficiently to cushion the shocks such as those produced by ordinary walking, the stiffener may become substantially unyielding so long as the pressure of the foot continues to be maintained steadily against it so that substantially a positive support for the arch of the foot is then afforded. It may also be found desirable to form more than a single loop in the stiffener, thereby further increasing the resiliency of the stiffener. As shown, the stiffener is provided at its opposite ends with apertures 18 for the reception of suitable fastening means, such as one or both of the rivets 20 shown in Fig. 2, thereby firmly anchoring the stiffener in place at one end or at both ends as may be desired. Inasmuch as the loop is located substantially midway between the ends of the stiffener it will not be necessary to make any change in the construction of the shoe to receive the loop and the presence of the loop will not alter in any way the usual shape of the shoe bottom.

If, as shown, the stiffener is riveted at both ends to the shoe sole it will be evident that the opposite sides of the loop may approach each other under pressure tending to flatten or straighten the longitudinal arch of the stiffener, thus permitting the stiffener to flex or straighten even though its ends are anchored to the shoe. Furthermore, if both ends of the stiffener are anchored neither end will rub across the sole and thus injury to the sole from such rubbing action is avoided.

To prevent the forward extremity of the stiffener from injuring the outer sole in case it is preferred not to anchor the forward end of the stiffener in a given instance, this end may be formed with a slight upward curve, such as shown at 22 in Fig. 1, this construction insuring that the end of the stiffener will not dig into the outer sole in case it rubs somewhat over the surface of the sole as the stiffener changes its shape while the shoe is being worn.

Having described my invention, what I claim as new and desire to secure by Letters Patent of the United States is:

1. An arch supporting shank stiffener comprising an elongated longitudinally arched strip having a laterally offset loop substantially midway between its ends the opposite sides of which are constructed and arranged to yield in a general direction lengthwise of the strip under pressure tending to flatten the longitudinal arch of the strip.

2. A resilient shank stiffener consisting of a longitudinally arched strip having an integral transversely bent portion of the full width of the strip and located substantially midway between its ends for increasing the resiliency of the stiffener.

3. A shank stiffener consisting of a resilient strip arched longitudinally to conform

to the arch of a foot and formed with a U-shaped bend extending across the strip substantially at the middle of the arch for increasing the resiliency of the strip.

5 4. A shoe comprising an upper, a sole, and a longitudinally arched shank stiffener having a resilient, transverse loop between its ends, the loop being shorter than the height of arch of the stiffener and adapted to engage the sole to limit the straightening of the longitudinal arch of the stiffener.

10 5. A shoe comprising inner and outer soles spaced apart at the shank, a shank stiffener longitudinally curved to conform to the longitudinal arch of the innersole and located in the space between the inner and outer soles, said stiffener being formed with a transverse loop opening toward the innersole and spaced from the outer sole for imparting resiliency to the stiffener and limiting the straightening of the longitudinal curve of the shank stiffener.

15 6. In a shoe having inner and outer soles, a longitudinally arched shank stiffener located between the soles and having an integral looped portion bent at right angles to the length of the stiffener to adapt the sides of the loop to approach each other under pressure tending to straighten the arch of the stiffener, the closed end portion of the loop being located at the concave side of the stiffener to function as a stop to prevent excessive straightening of the stiffener, and rivets extending through the outer sole and through the opposite ends of the stiffener for rigidly securing the stiffener to the outer sole.

20 7. An arch supporting shank stiffener consisting of a longitudinally arched strip having a portion offset transversely of the strip substantially midway between the ends of the strip for limiting the extent to which the

strip may be straightened when the stiffener is incorporated in a shoe, the amount of the offset being less than the height of the arch 45 of the strip.

25 8. A shank stiffener comprising a longitudinally arched resilient strip transversely bent between its ends to provide an integral resilient stop projecting from the concave 50 side of the stiffener strip for engagement with the sole of a shoe in which the stiffener is to be incorporated to permit the longitudinal arch of the stiffener to be straightened only to a limited extent.

30 9. A resilient shank stiffener arched to conform to the longitudinal arch of a foot and having an integral U-shaped bend offset from the concave side of the stiffener an amount less than the normal height of the 55 arch for limiting the extent to which the stiffener is capable of straightening under pressure applied to the convex side of the stiffener.

35 10. A longitudinally arched stiffener having a resilient transverse loop between its ends, the loop being shorter than the height of the arch of the stiffener and adapted for engagement with the sole of a shoe in which the stiffener is to be incorporated to limit 60 the straightening of the longitudinal arch of the stiffener.

40 11. A shoe comprising inner and outer soles, and an arched shank stiffener interposed between said soles, said stiffener being 65 transversely bent substantially midway between its ends to provide a stop for engagement with the outer sole to limit the straightening of the arch of the shank stiffener and having its opposite ends riveted to 70 the outer sole.

In testimony whereof I have signed my name to this specification.

JAMES A. BROGAN.
